ATTORNEY

UNITED STATES PATENT OFFICE.

LEONARD R. CARLEY, OF WATERBURY, CONNECTICUT, ASSIGNOR TO PATENT BUTTON COMPANY, OF WATERBURY, CONNECTICUT, A CORPORATION OF CONNECTICUT.

TACK.

1,149,183.

Specification of Letters Patent. Patented Aug. 10, 1915.

Application filed November 3, 1913. Serial No. 798,842.

To all whom it may concern:

Be it known that I, LEONARD R. CARLEY, a subject of His Majesty the King of Great Britain, and a resident of Waterbury, in the county of New Haven and State of Connecticut, have made and invented certain new and useful Improvements in Tacks, of which the following is a specification.

My invention relates to an improvement in tacks, and more particularly to that kind or type thereof used or employed in connection with buttons, or like articles, for the purpose of attaching the latter to cloth or fabric.

15 In the manufacture of tacks, having a cap stamped around the head and bent to finally cover the same, it has heretofore usually resulted in the head being rough and irregular, due to the metal folding upon itself.

20 An object of this invention is to do away with the foregoing disadvantages and also to provide a tack wherein the capped head is solid to all practical purposes with the shank of the tack.

25 With these and other ends in view, the invention consists in certain novel features of construction and combinations of parts as will be hereinafter fully described and pointed out in the claim.

30 In the accompanying drawings, Figure 1 is a view of the cap blank; Fig. 2 is a perspective view of the same after being drawn up into the form of a shell, and Fig. 3 a sectional view of the same; Fig. 4 is a view 35 in perspective showing the shell partially closed over the head of the tack, and Fig. 5 a sectional view of the same. Fig. 6 is a view in elevation of the finished tack, and Fig. 7 a view of the same partly in elevation and 40 partly in section; Fig. 8 is a plan view of the finished tack, looking at the under side of the capped head.

45 By reference to these drawings it will be seen that my improved tack is made up of the ordinary tack of commerce, that is, a tack comprising a sharpened or pointed shank A, and having the ordinary head B formed integral therewith. In capping this head, I first form a square blank, C, Fig. 1, which by means of suitable dies, (not shown), is cupped or drawn up into the form of a shell D' provided with four points D, these pointed ends corresponding

with the four corners of the square blank. In the formation of this shell, it will be seen by reference to Fig. 2, that there is formed a circular wall or flange D² surrounding the closed end D³ thereof, and from which wall or flange extends the four points, the diameter of the shell being considerably larger than the head of the tack to be capped, as illustrated in Figs. 5 and 7. Within this shell is placed the head of the tack, the circular wall D² of the shell being subsequently bent inwardly and downwardly upon the under side or surface of the tack head B, this operation resulting in bringing the edges of the pointed ends together, as illustrated in Fig. 8, the extreme pointed ends being somewhat flattened 70 against the shank A of the tack. In the resulting article, there is therefore no crimping, bending, or folding of the metal of the cap over and upon itself.

75 By reference to Fig. 8 of the drawings it will be seen that the circular wall D² of the shell D' when folded inwardly upon the under side of the tack head, extends from the outer edge of the cap to approximately the outer edge of the head B formed integral with the shank A of the tack, the edges a of the pointed ends D, and which originally formed the edges a of the blank, abutting against each other on a line running 80 or extending from the circular wall to the 85 shank of the tack.

For the purpose of tightly and securely holding the head of the tack within the cap, I bend inwardly the metal of the cap on its under side around the outer edge of the 90 tack head, the resulting article showing a circular groove E, as illustrated in Fig. 7 of the drawings.

From the foregoing it will be seen that my improved tack will be smooth, regular, 95 and neatly capped, that it can be easily and economically manufactured, and that no loss or scrap results.

What I claim is:—

An article of the class described, comprising a tack including a head and shank, a cap, the central portion of which contacts with the outer face of said tack head, triangular corners of said cap extending across the inner or opposite face of said head and impinging against the said shank, said cor- 100 105

ners defining locking flaps, said flaps provided intermediate their ends with transversely extending internal ribs, said ribs extending below the inner face of said head and abutting against the edges thereof.

Signed at New York, borough of Manhattan, in the county of New York and

State of New York, this 31st day of October, A. D. 1913.

LEONARD R. CARLEY.
